METHOD FOR APPLYING LATEX TO
DEPOSITION BASES

Merrill E. Hansen, Akron, Ohio, assignor to American Anode, Inc., Akron, Ohio, a corporation of Delaware

Application January 6, 1936, Serial No. 57,694

10 Claims. (Cl. 18—57)

This invention relates to procedure and apparatus for applying coatings of latex to deposition bases, especially deposition bases in continuous strip or sheet form, and may be employed either for providing permanent coatings of latex rubber upon such bases or for making strips or sheets of rubber by removing the deposited rubber from the deposition bases. Thus, the invention may be used for permanently coating paper, textile fabric or the like on one or both sides with latex rubber, or for making threads, strips, or sheets of latex rubber of any desired gauge and width. In either adaptation the invention possesses distinct operating and economic advantages, in addition to producing superior products.

In its broad aspects, the present invention comprises utilizing a deposition base of suitable form which is floatable upon the surface of the latex or other liquid material to be applied to the deposition base, and in floating the base upon the surface of the latex or other material to receive the desired coating. Through this novel procedure one side only of, for example, a sheet of textile fabric may be uniformly coated with any desired thickness of latex rubber without applying any substantial amount of latex to the other side of the fabric. Heretofore, this could be accomplished only by using relatively complicated and expensive spreaders or the like, and can never be accomplished if the fabric is immersed in the latex as in the procedures for treating fabric with latex now most commonly used. Similarly, strips or sheets of rubber may be made by stripping the deposited rubber from the deposition base, without any of the inconvenience and waste accompanying the use of deposition drums or bands immersed in latex where rubber must always be deposited on portions of the drum or band in addition to the desired portions, and without the expense and operating difficulties accompanying processes such as those in which latex is printed onto the deposition surfaces.

Other advantages will be apparent from the following detailed description of the invention as exemplified by preferred embodiments, in which reference will be made to the accompanying drawings of which;

Fig. 1 is an elevation in diagrammatic form illustrating the present invention applied to the coating of fabric;

Fig. 2 is a similar diagrammatic elevation illustrating apparatus for making rubber in sheet form;

Fig. 3 is a vertical section taken on the line 3—3 of Fig. 2;

Fig. 4 is an enlarged vertical section showing a deposition base used for making rubber thread according to the present invention with a deposited rubber thread thereon;

Fig. 5 is a vertical section similar to Fig. 3 illustrating a modification of the invention in which fibrous material to be impregnated and/or coated with latex is floated upon the surface of the latex together with a superposed sheet deposition base;

For the purpose of illustrating the coating of fabric or other material with latex using the present novel method, I have chosen to describe applying two coatings of latex rubber to the same face of a sheet of fabric, leaving the other face entirely uncoated and without any latex, although it is to be understood that through utilization of the principles to be described, one or more than one coating of latex rubber may be applied to either or both sides of the fabric by suitable repetition of the coating operation.

In a specific embodiment of the invention, illustrated in Fig. 1, a roll of textile fabric 10 to be coated is mounted upon a suitable support 25 for unwinding and the fabric is directed over a number of positively driven rollers designated in succession, 11, 12, 13, 14 and 15, and then to a rewinding station 16. The several rollers preferably have fabric-gripping surfaces and are so disposed and their direction of rotation is such that the fabric in passing from the roll 10 to the rewinding station 16 is caused to travel along a path including two free loops, the path being so arranged, in this example, that the same face 30 of the fabric is exposed at the bottom of each of the two loops.

Under the bottom of each of the two fabric loops is provided a container, designated respectively 17a and 17b, each containing liquid rubber latex 18a and 18b suitably compounded, the level of the liquid latex in each container being somewhat higher than the normal lowermost portion of the loop so that a substantial portion of the looped fabric will be in contact with and floating upon the surface of the latex. It will immediately be appreciated that close adjustment of the latex levels in the containers is not necessary as the looped fabric will automatically 45 adjust itself to any variations in the level of the latex.

A drying chamber 19, heated as by circulating hot air, is provided about a reach of the fabric in its travel between the two latex containers, 50 55

and a similar dryer 20 is disposed about a reach of the fabric past the second latex container. For coating most materials the dryers may be disposed as shown in the drawings, but if the material being coated has a reticulate structure as for example very coarsely woven fabric, it may in some cases be desirable to place the dryers about the reaches of the fabric just after it leaves the latex in order to dry the latex upon the fabric at least partially before the coated fabric passes over the driving rollers and thereby to eliminate the possibility of uncoagulated latex flowing through the reticulate structure onto the rollers. Following the second dryer 20, a vulcanizing chamber 21, suitably heated, is provided about the fabric. The fabric of course may be caused to traverse the length of the dryers and/or vulcanizing chamber more than once to effect the requisite heating for drying and vulcanization.

Having arranged the fabric and apparatus as described, the several driving rollers are rotated at a suitable speed which, for example, will cause the fabric to travel at a rate of about five lineal feet per minute although considerable variation in speed, say from two to ten feet per minute, is possible without materially affecting the mode of operation. The rollers cause the fabric to travel along the path indicated, bringing it first into progressive floating contact with the surface of the latex in the first tank 17a from which it picks up a thin coating of latex 22a and then is progressively withdrawn from the latex and passed through the dryer 18 operated for example at a temperature of 160-180° F. The apparatus is arranged so that the once-coated fabric is in the first dryer for a time sufficient to set the latex firmly, a period of about five to ten minutes at the temperature indicated usually being satisfactory. The fabric with its somewhat dried coating of latex, continuing the travel along the path indicated, is brought into progressive floating contact with the surface of the latex in the second container 17b from which it picks up a second coating of latex over the first forming a composite coating of latex rubber 22 upon the fabric. The coated fabric then is thoroughly dried in the second dryer 20, for example about thirty minutes at 180° F. and the rubber coating is vulcanized as the fabric passes through the vulcanizer 21 operated at a suitable temperature dependent upon the characteristics of the particular latex composition in use. The finished fabric then is rewound or otherwise disposed of at the station 16.

Utilizing a compounded latex containing 50% total solids and having a viscosity of about two and one half times that of water, the over-all thickness of a sheet of closely woven cotton fabric was increased by approximately 0.005" by applying two coatings of latex in the manner described.

If substantial impregnation of the fabric is desired, the fabric may be pre-treated with a wetting agent before treatment with latex, or a wetting agent may be added to the latex itself to facilitate wetting and impregnation of the fabric by the latex. Such use of wetting agents is well known and will be understood without detailed explanation here.

The present invention has been successfully used for coating and impregnating a wide variety of fibrous sheet materials including cotton, wool, silk, artificial silk, and the like, both closely woven as in fine silk fabrics or loosely woven as in cheese-cloth, as well as felted fibrous sheets including paper. All such fibrous sheet materials

float upon the latex and may be efficiently coated or impregnated with latex in the manner described. Non-fibrous materials may be coated in a similar manner, and the invention has been successfully used for coating thin sheets of light metals such as aluminum foil.

In applying the present invention to the manufacture of rubber threads, strips, or sheets, all of which will hereinafter be referred to simply as rubber strips, or as rubber in strip form, I preferably employ a floatable deposition base to which the deposited latex rubber will not adhere so tenaciously as to render stripping of the rubber from the base unduly difficult. For this purpose, I have used bands of paper, fabric preferably suitably treated to prevent tenacious adhesion of the rubber such as fabric coated with rubber, rubber bands alone, and even thin flexible sheets of light metals such as aluminum foil, all of which float upon the latex. It is desirable however to provide for continuous operation by providing an endless deposition base, and for this purpose I have found a fabric band or belt, preferably coated with vulcanized rubber, to be quite satisfactory.

Such a floatable deposition base 30, (Figs. 2 and 3) for example, may consist of an endless belt of closely woven cotton fabric 31 thinly coated on both faces with vulcanized rubber 32, 32. The rubber surface of the belt may be suitably treated, as with a halogen, to render it less likely to adhere to the deposited latex rubber, but for reasons hereinafter to be indicated, such treatment will not be necessary in my preferred process.

The endless deposition base or belt 30 is caused to travel about a series of positively driven rollers having frictional belt-gripping surfaces designated in succession 33, 34, 35, 36, 37 and 38 and past idler guide rolls 39, 39 and a belt adjuster 40, the several rolls being so arranged and their direction of rotation being such that the deposition base in its continuous travel is caused to traverse a path including two free loops and, after the second of the two loops, a relatively long nearly horizontal reach. The arrangement of the rollers also is such that the same face of the deposition base is exposed at the lowermost portions of both the loops and so that this same face is uppermost when travelling along the nearly horizontal reach. The belt adjuster 40 is disposed at a reach of the deposition base between the end of the horizontal reach and the first loop.

A tank 41 containing a liquid coagulant 42 for rubber latex is placed at the bottom of the first free loop of the deposition base and a second tank 43 containing suitably compounded liquid rubber latex 44 is placed under the second loop of the base, with the liquid levels in both tanks somewhat higher than the normal lowermost portions of the two loops so that a substantial portion of each of the two loops is in floating contact with the respective liquids.

Adjacent the end of the long nearly horizontal reach of the deposition base is provided a washer consisting of a tank 45 containing water 46 and, above the water, a spray pipe 47 adapted to direct a series of sprays of wash water downward upon material floating on the surface of wash water in the tank.

A drying chamber 48 heated as by circulating hot air and including a suitable conveyor 49 passing through the dryer is provided adjacent the end of the washer, and a suitably heated vulcanizing chamber 50 including a conveyor 51 passing through the chamber is provided adjacent the

dryer. Finally a wind-up station 52 or other desirable strip collecting apparatus is provided near the exit end of the vulcanizing chamber.

As may readily be appreciated from the drawings (Fig. 2) the endless deposition base in its continuous travel in the direction and along the path indicated will first be brought into progressive floating contact with the liquid coagulant 42 and that one face of the base will pick up a film or coating of the liquid coagulant, usually a solution of a polyvalent metal salt in a volatile solvent, and that the film or coating will dry somewhat as the base travels from the coagulant. Next the coagulant coated face is brought into progressive floating contact with latex 44 and a coating of latex coagulum 53 will be deposited upon the base as it floats across the surface of the latex. The belt then will leave the latex carrying with it the coagulum which is permitted to become firmly coagulated and to dry somewhat as the base travels along the relatively long nearly horizontal reach. The coagulum 53 is removed from the deposition base without difficulty because of the separating qualities of the coagulant, and is thoroughly washed as by floating the coagulum upon wash water and at the same time spraying water upon the exposed face to remove residual coagulant and other water-soluble materials, after which the coagulum is transported through the dryer and vulcanizer. Finally the finished rubber strip is collected as by winding upon an arbor, or otherwise disposed of.

In making rubber strips in the manner described, details of operation will be varied as required in individual cases and as will be understood by the skilled artisan. For purposes of illustration, however, a typical set of materials and conditions which have been used for making rubber sheet 0.012 to 0.015 inch thick will be described.

In a typical example, the endless deposition base is caused to travel at a constant rate of about seven feet per minute. The coagulant tank 41 may be about two feet long, and the latex tank 43 may be about nine feet long so that the base will be in contact with the coagulant for approximately one fourth of a minute and in contact with the latex for approximately one minute. The apparatus should be so arranged that about one minute elapses while the base travels from the coagulant to the latex and so that about two minutes elapse while the base travels from the latex to the point at which the coagulum is removed from the base. The dryer 48 may be operated at 160 to 180° F. and the vulcanizer 50 at 220° F.

The liquid coagulant 42 may be a solution of 150 grams of calcium chloride dissolved in 1000 cc. of methanol containing 20 grams of lactic acid as a wetting agent. The latex 44 may be an aqueous dispersion having a total solids content of 50% and containing 100 parts by weight of rubber added as the concentrated latex of commerce, 1.5 parts of sulfur, 1.0 part of zinc oxide, 0.45 part of an organic accelerator, and 0.1 part of an age-resister.

In a further modification of the present invention illustrated in Fig. 4, rubber strips of U shaped cross section suitable for use as rubber thread have been made by progressively floating upon latex in the manner described a filamentary deposition base of circular cross section consisting of a small fibrous cord 60 coated with vulcanized rubber 61 to provide a smooth deposition surface. In this procedure, latex deposits upon

approximately half the circumference of the cord producing a U shaped strip of coagulum 62 which for example may be folded or rolled to form a substantially circular thread and wrapped with textile materials for use in stretchable garments. 5

Numerous modifications of the invention as hereinabove described are possible. If thin strips of rubber are to be made, application of coagulant to the deposition base may be omitted in which case it may sometimes be desirable to treat the 10 latex upon the deposition base with coagulant in liquid or vapor form after the base leaves the main body of latex. For making thicker strips, the concentration of the coagulant and the time of contact with the latex may be increased, or the 15 strip of coagulum may be removed from the deposition base and the coagulum strip itself progressively floated across a second body of latex to build up a thicker strip. If a coagulant or coagulant composition having a low specific 20 gravity is used, the deposition base may be immersed in the coagulant rather than floated upon its surface as described. Similarly, fabric to be coated may be pre-treated with coagulant in which case the rubber deposit will be more superficial than otherwise would be the case, or the 25 latex after its application to the fabric may be treated with coagulant. It is also possible to float fabric, either wefted or weftless, together with a superposed sheet deposition base upon the 30 latex in which case the fabric will be entirely submerged and therefore will be completely embedded in the deposited rubber. Such procedure is especially useful for making rubber impregnated and coated fabrics for pneumatic tire 35 manufacture. For example, referring to Fig. 5, the apparatus of Fig. 2 may be utilized for impregnating and coating tire cord fabric by progressively passing a sheet of tire cord fabric 65 in floating contact across the surface of the latex 44 together with the superposed sheet deposition base 30. As the fabric 65 is underneath the somewhat heavier deposition base 30, the fabric will be substantially submerged in the latex and will receive a satisfactory impregnating and coating deposit of latex which is dried but not vulcanized, of course, if it is to be used in tire manufacture. If a rubber coated sheet is desired for other purposes, the coating obviously may be vulcanized as well as dried merely by passing the 40 treated fabric through suitable heaters as in 45 Fig. 1.

It is of course also understood that any of the well known coagulants for latex such as those disclosed in Willson U. S. Patent No. 1,996,090 may be used in the present process and that the term "latex" or "liquid rubber latex" as herein used is intended to include all naturally occurring or artificially prepared analogous aqueous dispersions or emulsions of natural or synthetic rubber, the 55 term "rubber" including caoutchouc, gutta percha, balata, and like gums, resins and synthetic products, whether such dispersions be concentrated, diluted, thickened, thinned, stabilized, compounded, or otherwise prepared or conditioned for use. As has been indicated, the term "strip" or "strip form" is intended to include not only relatively narrow flat strips in the ordinary sense of the word but also filaments, bands, sheets and the like. 60

All such modifications and variations are within the scope of the present invention as defined by the appended claims.

I claim:

1. The method which comprises providing a 75

- body of liquid rubber latex, providing a deposition base in strip form floatable upon the surface of the latex, bringing the deposition base progressively into floating contact with the surface of the latex, progressively removing the deposition base together with solids from the latex, and drying the latex solids. 5
2. The method which comprises providing a body of liquid rubber latex, providing a deposition base in strip form floatable upon the surface of the latex, causing the deposition base to travel in a looped path with the bottom of the loop in progressive floating contact with the latex, and drying latex solids upon the strip after its contact 10 with the latex. 15
3. The method which comprises providing a body of liquid rubber latex, providing a body of liquid coagulant for the latex, providing a deposition base in strip form floatable upon the surface 20 of at least one of the aforesaid two liquids, bringing the deposition base into contact successively with the coagulant and with the latex, at least one of the successive contacts being a progressive floating contact of the base with the liquid, and 25 drying the resulting rubber coagulum.
4. In a method for depositing rubber directly from liquid rubber latex onto a deposition base, the process which comprises the step of floating the deposition base upon the surface of the latex. 30
5. In a method for depositing rubber directly from liquid rubber latex onto a deposition base by successively applying latex and fluid coagulant to the base, the method which comprises the step of floating the deposition base upon the surface of at 35 least one of the two aforesaid materials.
6. The method of producing rubber in strip form which comprises providing a body of liquid rubber latex, providing a deposition base in strip form floatable upon the surface of the latex, bringing the deposition base progressively into 40 floating contact with the surface of the latex to receive a deposit of latex solids, and removing the deposited solids from the deposition base in strip form. 5
7. The method of producing rubber in strip form which comprises providing a body of liquid rubber latex, providing a body of liquid coagulant for the latex, providing a deposition base in strip form floatable upon the surface of at least one of the two aforesaid liquids, bringing the deposition base into contact successively with the coagulant and with the latex, at least one of the successive contacts being a progressive floating contact of the base with the liquid, and removing the resulting coagulated rubber from the deposition base in strip form. 10 15
8. The method of applying rubber to material which comprises floating the material upon the surface of a body of liquid rubber latex, removing the material together with associated solids from the latex, and drying the latex solids upon 20 the material. 25
9. The method of applying rubber to relatively long lengths of sheet material which comprises bringing the sheet material progressively into floating contact with the surface of liquid rubber latex, progressively removing the sheet material together with associated solids from the latex, and drying the latex solids upon the material. 30 35
10. The method of applying rubber to relatively long lengths of fibrous material which comprises bringing the fibrous material together with a superposed impervious sheet deposition base into progressive floating contact with the surface of liquid rubber latex, progressively removing the fibrous material and superposed deposition base together with associated solids from the latex, separating the fibrous material and associated latex solids from the deposition base, and drying the latex solids on the fibrous material. 40

MERRILL E. HANSEN.
